PORTABLE SANITARY COMFORT SEAT FOR CHILDREN

Harold Clyde Hess, Decatur, Ill.

Application March 30, 1938, Serial No. 199,041

4 Claims. (Cl. 4—137)

This invention relates to a portable sanitary comfort seat for children, and more particularly to a device of this type adapted for compactness, convenience and neat appearance in motorcar traveling.

An object of the invention is the provision in a device of this type, of a neat appearing and compact closure for a comfort vessel of the type hereinafter described and shown in the drawing, 10 while at the same time rendering said vessel easy of access for use or cleansing.

Another object is the provision of a closure such as above mentioned, so constructed and formed 15 as to act as a concealment for its purpose, as, for example, while lying unused in the seat of a motorcar, or being carried to or from a motorcar.

A further object is the provision of a sanitary seat guard that may be readily brought into position for use or folded up in a concealed position 20 while not in use, and that may be easily detached for cleansing, and as easily replaced.

While traveling via automobile with small children a frequent source of great inconvenience and loss of time is the necessity for stopping en- 25 route for the comfort of the children. This means as well, the necessity of using public rest rooms some of which subject children to poor toilet facilities, together with unclean and unsanitary conditions.

30 My invention is constructed to render it possible to provide ready and convenient toilet comfort to a small child while traveling, without the inconvenience of stopping the motorcar, and to provide as well, personal equipment of this type 35 of assured cleanliness.

My invention is also adaptable to bathrooms and toilets in homes where the children are too small to use the standard equipment.

In order that the nature and construction of 40 the invention may be more readily understood, one form of construction is described with reference to the accompanying drawing, wherein like numerals indicate like parts throughout.

Fig. 1 is a side sectional view of the cabinet or 45 closure, the vessel and the seat guard being in elevation as in position for use, the lid being shown partly up and the door open fully.

Fig. 2 is a front elevational view taken trans- 50 versely of Fig. 1.

Fig. 3 is a fragmentary plan view of the under surface of the seat portion, showing particularly the detachable seat guard, the dotted lines showing the position of said seat guard when folded back out of use.

55 Fig. 4 is an enlarged perspective view of the

seat guard, as engaged by a pair of supporting members, less the angle members.

Fig. 5 is a sectional view of the seat guard detached, taken across one of the sockets.

Fig. 6 is a side elevational view of one of the 5 supporting members.

Fig. 7 is an enlarged perspective view of the spring yoke.

The invention comprises a substantially square shaped cabinet or box 10, having hingedly connected to one side of its top the lid 11, the top or seat 12 of said box 10 having a relatively large aperture 13 centrally therethrough, a detachable seat guard 14 is mounted integrally on the under surface of the said seat 12 adjacent to one side 15 of the said aperture 13, and is adapted to protrude upwardly through said aperture 13 as shown particularly in Figs. 1 and 2, by means of the substantially right-angularly shaped supporting members 15 which are adapted to operate con- 20 jointly with each other, having at one end the formed eyelets 16 which pivotally engage the pair of angle brackets 17 by means of the rivets 18 and having at the other end the right-angularly formed fingers 16' adapted to slidably engage the 25 sockets 14' of said seat guard 14 for the purpose of enabling said seat guard 14 to be detached for cleansing.

Said angle brackets 17 are secured to the under surface of said top 12 by means of the wood 30 screws 19 projecting through the through holes 17' in the feet 20 of said angle brackets 17.

The spring yokes 21 and 22 are mounted in spaced relation to and oppositely of each other. The seat guard 14 is pivoted into position as 35 indicated by the solid lines in Figs. 1 and 2 by means of manually pressing the pair of supporting members 15 against the spring yoke 21 to slidably engage the spring member 23 thereof until said supporting members 15 are thus moved 40 into the grooves 24 and are there held in fixed position until disengaged.

To disengage the seat guard 14 and pivot it into concealed position as indicated by the dotted lines in Figs. 1 and 2 the supporting members 45 15 are released from engagement with the spring yoke 21 by the hand of the operator and then pivoted into similar engagement with the spring yoke 22. Said spring yokes 21 and 22 are secured to the under surface of the top 12 by means of the 50 wood screws 25 protruding through the through holes 26 disposed centrally in said spring yokes 21 and 22.

A pair of parallelly and integrally disposed track members 27 is mounted inside the box 10 55

as shown particularly in Figs. 1 and 2, said track members 27 being adapted to engage in slidable relation thereto the flanged rim 28 of the vessel 29, said vessel 29 being thereby enabled to slide in and out of said box 10 at the will of the operator.

The hinged door 30 provides easy access to and concealment of the vessel 29, while the hinged lid 11 conceals the top of the seat 12, thus imparting a neat appearance to the invention, particularly when not in use.

With the foregoing description of this device in connection with the accompanying drawing it is thought that its novel though simple arrangement and construction is clearly evident, and while I show but one type of structure it is to be understood that such changes in details of construction as may be made to suit the requirements of the purpose for which the device is intended 20 may be made within the scope of the appended claims without departing from the spirit of the invention.

I claim:

1. In a portable comfort cabinet comprising a 25 housing having a horizontally disposed seat cover with an opening therethrough, a detachable semi-circular guard plate hingedly secured to the underneath side of said seat cover and adapted to be raised to vertical position inside the edge of 30 said opening, and spring means mounted on said seat cover for holding said guard plate in raised and lowered positions, respectively.

2. In a portable comfort cabinet comprising a 35 housing having a horizontally disposed seat cover with an opening therethrough, a detachable semi-circular guard plate hingedly secured to the underneath side of said cover, said guard plate being adapted to be raised to vertical position inside

the edge of said opening, spring means mounted on said seat cover for holding said guard plate in raised and lowered positions respectively, and means carried by said guard plate for detaching it from said seat cover.

3. In a portable comfort cabinet comprising a 5 housing having a horizontally disposed seat cover with an opening therethrough, a detachable semi-circular guard plate hingedly secured to the underneath side of said seat cover, a pair of sockets on said guard plate, said sockets being adapted to detachably receive the ends of supporting rods 10 hingedly mounted on said seat cover, said supporting rods enabling said guard plate to be raised to normal position inside the edge of said 15 opening and to be folded back underneath said cover away from said opening, and spring grip means mounted on said cover and adapted for engagement with said rods to hold same in normal or folded positions.

4. In a portable comfort cabinet comprising a 20 housing having a horizontally disposed seat cover with an opening therethrough, a detachable semi-circular guard plate having a pair of sockets 25 on its outer surface spaced apart from each other, a pair of rods having one end of each bent at a right angle for insertion in said sockets and having the other end formed into an eye through which said rods are pivotally secured to a pair of brackets attached to the underneath side of said 30 cover to permit said guard plate to be hingedly moved forwardly to a position within said opening or folded rearwardly away from said opening, and a pair of spring grip members, so located as to engage each of said rods at intermediate 35 points therefrom to hold said rods and guard plate in either normal or folded position.

HAROLD CLYDE HESS.
